UNITED STATES PATENT OFFICE.

FREDERICK EDMUND BERRY, OF HAYES, ENGLAND.

ELECTRIC FURNACE AND TRANSFORMER FOR USE THEREWITH.

1,299,664.

Specification of Letters Patent.

Patented Apr. 8, 1919.

Application filed January 19, 1918. Serial No. 212,747.

To all whom it may concern:

Be it known that I, FREDERICK EDMUND BERRY, a subject of the King of Great Britain and Ireland, residing at Hayes, in the 5 county of Middlesex, England, have invented Improvements in or Relating to Electric Furnaces and Transformers for Use Therewith, of which the following is a specification.

10 This invention has reference to improved arrangements of three phase transformers and electric furnaces, designed to give a better distribution of heat through the bulk of the metal or charge in the furnace and a better mixing of the molten metal or charge, 15 than with the arrangements heretofore used.

For this purpose in a transformer arrangement and electric furnace according to the invention there is used a three phase 20 transformer the primary windings of which can be delta or star connected, or inter-connected star, or be a combination of such groupings, but the secondary windings of which are so arranged that each phase is 25 brought out to separate terminals so as to give at the transformer itself a separate circuit for each phase. The secondary windings may be connected up in any of the known ways so long as a separate circuit is 30 provided for each phase.

The three phase transformer may be constructed as a single structure, or three single phase transformers may be coupled up for three phase working as well understood.

35 The three pairs of terminals of the secondary windings are combined with an electric furnace in such manner that three of them form an upper set of terminals or electrodes and the other three are disposed at the lower 40 part of the furnace, to form a lower set of terminals or electrodes that are spaced apart and are in contact, it may be, with the lining of the furnace and in electrical connection with the metallic charge in such furnace.

45 In order that the invention may be readily understood it will now be further described with the aid of the drawings filed with our provisional specification.

In these drawings, Figure 1 shows, diagrammatically, a three phase transformer and electric furnace according to the invention and Fig. 2 is a plan showing the relative positions of the secondary terminals or electrodes in the furnace.

55 For simplicity, Fig. 1 shows a three phase transformer having its primary windings

a, b and *c* delta connected and its secondary windings arranged to form three separate windings *d, e* and *f*.

The corresponding ends of the secondary 60 or phase windings *d, e* and *f* are connected to electrodes 1, 2 and 3 at the top of the furnace and the opposite ends of such windings are connected to terminals 1^a, 2^a, and 3^a arranged in the lower part of the side portions of the furnace so as to make contact with the metal charge therein at the periphery thereof, or, as is more usual, with the lining of the furnace which, at a high temperature, is conducting so that the circuit 70 through the metal is completed through such lining.

The relative positions of the electrodes 1, 2 and 3 and terminals 1^a, 2^a and 3^a in the furnace may be varied. Thus, the positions 75 of the electrodes 1, 2 and 3 in the upper part of the furnace may be the reverse of those of the terminals 1^a, 2^a and 3^a in the body of the furnace, as shown in Fig. 1, so that the movement of the metal in the upper part 80 of furnace, due to the current and to the electromagnetic effect of such current, will be in the opposite direction to the movement of the metal in the lower part of the furnace, so as to more efficiently mix the metal and 85 bring all parts thereof under the influence of the heat produced by the passage of the current through the furnace.

The described arrangement of the transformer and the electrodes and terminals connected thereto, constitutes in effect, a six phase connection to the furnace. Each of the circuits 1 to 1^a, 2 to 2^a, 3 to 3^a, are single phase circuits but the effect of the currents at the electrodes 1, 2 and 3 and also at the 90 terminals 1^a, 2^a and 3^a is to give a three phase distribution with corresponding movement and mixing of the metal in the furnace, and, as hereinbefore stated, the disposition of the electrodes 1, 2 and 3 and the 95 terminals 1^a, 2^a and 3^a may be such as to create opposite movements in the metal influenced at these positions so as to improve the mixing of the metal.

The secondary winding *d, e*, or *f* of each 105 phase should be so designed as to give the correct voltage necessary to supply the current required against the resistance of the arc between the corresponding electrode 1, 2 or 3 and the metal, the resistance of the 110 metal and the resistance between the metal and the terminal 1^a, 2^a or 3^a in the furnace

lining, in addition to the resistance of the winding itself and the connections external to the transformer and furnace.

If necessary, when starting up the furnace, or at any subsequent period if desired, the terminals 1^a, 2^a and 3^a in the furnace lining may be short circuited by a suitable switch, either actually at the terminals themselves or at the terminals of the transformer windings that are connected to these points. In this case the arrangement becomes that of a simple three phase supply.

The transformer may of course be fitted with primary or secondary tappings for varying the voltage to the furnace as required.

By the arrangement described a better distribution of the heat in the furnace is effected and a better mixing of the metal or charge in the furnace obtained, whereby a more efficient working of the furnace is insured and smaller electrodes can be used for the same heating effect than with other arrangements of combined transformer and electric furnace heretofore used.

What I claim is:—

1. A three phase electric furnace having upper electrodes arranged above the furnace charge and lower and laterally arranged electrodes in electrical connection with said charge when the furnace is in operation each of said lower electrodes being of such dimensions and so arranged that it is located wholly at a part of the furnace wall that will be between the top and bottom of the furnace charge when the furnace is in action.

2. A three phase electric furnace according to claim 1, wherein each of the lower electrodes is embedded in the side wall of the furnace and above the bottom of the furnace so that it will be separated from the furnace charge by part of the refractory wall of the furnace.

3. A three phase electric furnace according to the claim 1, wherein the polarities of the electrodes in the upper part of the furnace are the reverse of those in the lower part thereof.

4. A three phase electric furnace having upper electrodes arranged above the furnace charge and lower and laterally arranged electrodes in electrical connection with the said charge when the furnace is in operation, each of said lower electrodes being of such dimensions and so arranged that it is located wholly at a part of the furnace wall

that will be between the top and bottom of the furnace charge when the furnace is in operation, and means whereby the lower electrodes can, when desired, be temporarily short circuited outside the furnace.

5. A three phase electric furnace according to claim 1 combined with three secondary winding of a transformer, said windings being separate from each other and each having its two ends connected respectively to an upper electrode and a lower electrode.

6. An electric furnace and a three phase electrical transformer having a delta connected primary winding and three separate secondary windings, said furnace having three pairs of upper and lower electrodes, each pair being connected to the ends of one of said separate secondary windings and each of the lower electrodes being of such dimensions and so arranged that it is located at a part of the furnace wall that will be between the top and bottom of the furnace charge when the furnace is in action.

7. An electric furnace and a three phase electrical transformer having a delta connected primary winding and three separate secondary windings, said furnace having three pairs of upper and lower electrodes, each pair being connected to the ends of one of said separate secondary windings and each of the lower electrodes being of such dimensions and so arranged that it is located at a part of the furnace wall that will be between the top and bottom of the furnace charge when the furnace is in action and is covered with refractory material that will be conducting when the furnace is in action.

8. An electric furnace and a three phase electrical transformer having a delta connected primary winding and three separate secondary windings, said furnace having three pairs of upper and lower electrodes, each pair being connected to the ends of one pair of separate secondary windings and each of the lower electrodes being of such dimensions and so arranged that it is located at a part of the furnace wall that will be between the top and bottom of the furnace charge when the furnace is in action and a short circuiting device adapted to short circuit the electrical connections between the lower electrodes and the corresponding ends of the separate secondary conductors.

Signed at London, England, this 21st day of December, 1917.

FREDERICK EDMUND BERRY.
